UNITED STATES PATENT OFFICE

2,018,920

RETAINING WALL

Herbert B. Mette, Lakewood, Ohio

Application March 23, 1934, Serial No. 717,124

7 Claims. (Cl. 61—39)

This invention relates to the art of retaining walls and is an improvement upon my Patent Serial No. 1,909,299, May 16, 1933, to which reference may be had for a fuller understanding of the present invention.

In the present case there may be employed the same form of frame structure as is shown in my patent above referred to, and for purposes of illustration, I have here indicated this same frame structure, although it is to be understood that any suitable form of frame may be employed so far as the present improvement is concerned.

The object of the present invention is to devise an improved form of panel unit for use in the same type of retaining wall as is disclosed in my prior patent above referred to.

More specifically, the object is to devise a form of panel unit that will distribute the load to the frame-work, thereby eliminating side-thrust.

It is also within the purview of the present invention that my improved form of panel might be employed for the same general purpose in other specifically different constructions. That is, my new form of panel might be employed wherever in a construction of wall or the like, the distribution of applied load and the elimination of thrust becomes a material consideration.

In addition to the objects hereinbefore stated, other objects and purposes of use of the present invention will appear from the following description and claims when considered together with the accompanying drawing.

Fig. 1 is a perspective view of a retaining wall embodying my present invention;

Fig. 2 is a horizontal sectional view of a portion of my improved wall and indicates especially the panel structure;

Fig. 3 is a view taken on line 3—3 of Fig. 2;

Fig. 4 is a perspective view illustrating a portion of a panel unit;

Fig. 5 is a view similar to Fig. 4 but shows a modified form; and

Fig. 6 is another view similar to Fig. 4 and shows a still further modification.

As in my prior patent above referred to, so also here the frame structure to which the panels are applied for forming the wall proper and which are adapted to support the same, is fabricated from various forms of metallic members such as T-bars, channel members, I-beams, angle irons, etc., which may be adopted of any desired size and formed of any desired length, accordingly to the specifications of any given construction.

As in the prior patented case, the skeleton

frame construction is partially fabricated prior to shipping the same to the field where it is to be erected, and after assembling the same in position, the metal panels which have already been pre-formed as duplicate parts, are attached to the supporting frame in tiers. Then with the retaining wall in completed form, the earth, etc., is filled in at the rear thereof in the usual manner and the engagement of the back-fill with the rear face of the panel members will further serve as a means of maintaining the same in proper position.

The frame construction will not be described in detail but the disclosure in my prior patent will be relied upon for a fuller understanding.

As in the other case, the trusses which brace and hold the wall in place include as part thereof the main upright members 7 and 8, which are here shown as of T-form. The lower transverse members 12 are of T-form, channel iron or other desired shape and extend between the end uprights 7 and the upright member 8 and are secured thereto.

There are also intermediate uprights 13 of T-form with their front sides applied to the vertical flanges of the upper transverse members 9 and 10 and the lower transverse members 12 and they are connected thereto.

Upon erection of the frame construction, the metal panels are applied thereto. These panel members are each formed from sheet metal and each comprises a flat front member 20 and a corrugated bowed or arched rear member 21. These companion members are connected together at their side edges in any suitable manner, as for instance, by welding or riveting or by engaging the edges of one member in grooves of the other. These companion members are so arranged that the convex side of the bowed member will be at the rear so as to receive and distribute the load and its engagement with the flat plate will prevent side thrust of the bowed member.

The curvature of the bowed member in each instance is in a direction transversely of the direction of extent of the supporting means for the panel, and the corrugations 21a extend in the same direction as the curvature, that is, horizontally in the present embodiment.

In one form of panel unit, (Fig. 4), the edge portion 20a is grooved and receives the edge of the member 21 which is indicated in Fig. 4 as being free of corrugations at its edge portions.

In the form of panel unit shown in Fig. 5, the edge portions of the members 20 and 21 are riv-

eted together, the rivets occurring at the points of contact 22.

In Fig. 6, the construction is the same as in Fig. 5 except that the members 20 and 21 are spot-welded together at the points of contact 23 instead of employing rivets.

The same manner of mounting the panel units is employed here as in the other patent referred to; that is, the lower panels are first placed in position and the others are placed one above the other throughout the entire height of the wall.

As a means of securing the panel units in position as they are applied, I employ the spring clips 24 which are secured in any suitable manner to the rearwardly extending flanges of the upright T-bars 7 and 8, as indicated in the drawing, this being the same means as employed in my prior patent. Any other suitable means may be employed for this purpose.

20 The main portions of the clips 24 are adapted to be engaged by the end portions of the panel units so as to snap past the same and thereby permit the edge portions of the panel units to become engaged between the flanges of the T-bars 7 and 8 and the angularly disposed clips 24 which snap back into their normal position as the panels are thus applied.

Thus, the panel members when applied, are supported one upon another with the horizontal flanges of adjacent flat members 20 in interengagement, and are maintained in such arrangement by means of the spring clips. The bottom edge of the flat member of each panel unit is flanged, as indicated at 20°, so as to engage over the adjacent plain edge of the flat member of the under-positioned panel unit, as indicated in Fig. 3. This same general form of supporting engagement is employed also in my prior patent. Likewise, the adjacent horizontal edge portions 40 of the bowed members of superposed panel units may also engage each other in the same manner so as to produce a substantially closed wall throughout both front and rear parts thereof.

Thus, with my present form of panel unit, there 45 is obtained a retaining wall of a double form. The corrugations lend added strength to the panel units and hence to the entire wall structure, the load being transmitted to the frame without side thrust. The load of the back-fill 50 will be impressed upon the arch of the bowed surface and will be distributed to the frame without side thrust of the panel member. This is accomplished by the combination of the flat and bowed panel elements secured together in the 55 manner explained. This means reducing to a minimum the danger of collapse of the panel units.

At the same time, there is still obtained for 60 the front of the wall a neat appearance which can be still further enhanced by application of a paint. If desired, either one or both of the panel members, in each case, can be galvanized.

What I claim is:

1. A retaining wall structure comprising a 65 metal frame, separate unitary metal panels, and means for securing said panels in assembly with the frame structure so as to form the wall thereof preparatory to filling in material at the back thereof, said panels each including a front flat

member and a rear bowed element having its ends affixed thereto and with its convex side towards the rear so as to distribute the load applied thereto to the frame.

2. A retaining wall structure comprising a 5 metal frame, metal panels, and means for securing said panels in assembly with the frame structure so as to form the wall thereof preparatory to filling in material at the back thereof, each panel including a flat element and a bowed element with its convex side towards the rear and the direction of the same being transverse to the direction of extent of the supporting means for the panel so as to distribute the load applied thereto to the frame. 15

3. A retaining wall structure comprising a 20 metal frame, separate unitary panels, and means for securing said panels in assembly with the frame structure so as to form the wall thereof preparatory to filling in material at the back thereof, said panels each including a flat metal member and a corrugated bowed element secured thereto with its convex side towards the rear so as to distribute the load applied thereto to the frame, and with the corrugation thereof extending 25 in the direction of the curvature of the bowed element.

4. A retaining wall structure comprising a 30 metal frame, separate unitary metal panels in assembly with the frame structure so as to form the wall thereof preparatory to filling in material at the back thereof, said panels including a substantially flat element and a rear bowed element anchored at the ends of its bow to the edge portions of said flat element, whereby the load applied 35 to the rear of the structure is distributed laterally to the frame without lateral thrust.

5. A structure comprising a supporting frame, 40 separate, self-contained metal panels, and means for supporting said panels in assembly with the frame, said panels each including a flat metal plate and a bowed metal member connected to the flat element and with its convex side arranged to receive the load and to distribute the same to the frame and to prevent side thrust. 45

6. A structure comprising a supporting frame, separate, self-contained unitary metal panels each including a flat metal plate and a bowed metal member connected at its ends to the edge portions of said flat plate, the convex side of each 50 panel arranged to receive the load so as to distribute the load to the frame laterally and to prevent side thrust, and means for supporting said panels in assembly with the frame.

7. A retaining wall structure comprising a 55 metal frame, separate unitary metal panels, and means for securing said panels in assembly with the frame structure so as to form the wall thereof preparatory to filling in material at the back thereof, said panels each including a front flat 60 member and a rear bowed element having its ends affixed thereto and with its convex side towards the rear so as to distribute the load applied thereto to the frame, the adjacent horizontal edge portions of the superposed panels being 65 flanged and having interengagement with each other.
